Patent expires October 31, 1962

7 Claims. (Cl. 92—43)

1

The present invention relates to a process and apparatus for producing sheets composed of mixtures of fibers and cement.

A process is already known for the production of pipes and other similar hollow bodies in which tubes are formed on a porous or permeable cylinder, inside of which a vacuum is applied, through the action of one or more vibratory feed-tables, conveniently operated around said cylinder.

In the above mentioned known process, the production of the pipe through the formation of a layer of the desired thickness on the cylinder after the latter has accomplished only one revolution is obtained.

Furthermore, this known process provides a vibro-compacting action, exerted simultaneously with the revolving motion and the application of vacuum in the inside of cylinder.

To produce cement sheets, for example, from mixtures of fibers and cement or the like, it is expedient to form, by the above specified process, a pipe of suitable length and diameter, which is then cut along a generatrix, and finally unwound on a plane. This system of cutting and unwinding is already known, and generally applied in pasteboard making by well known machines.

However, it is obvious that the above mentioned known process only permits intermittent or discontinuous production. Moreover, the amount of additional processing of the sheet produced in such a manner depends, at least to a certain extent, upon its length, and consequently upon the cylinder diameter. It follows that, after all, should sheets of various length be produced, either the cylinder has to be replaced to have a circumference substantially equal to the length of the desired sheet, or large losses of material in the form of scraps have to be suffered as the length of the formed sheet is trimmed to the desired dimension.

All of the above specified disadvantages can be prevented by combining the known process with a system which applies the vacuum in timed relationship to the action of feeding and vibro-compacting devices associated with the rotated cylinder in accordance with the present invention.

Accordingly, an object of the present invention is to provide a process which allows continuous production of sheets of constant width and indefinite length, or of successive sheets having constant width and a predetermined length.

It is also possible with a process embodying the invention to obtain sheets with already fin-

2

ished sides, by giving to the surface on which the sheets are formed a shape such as to sharply delimit the edges of said sheets, and/or to give to the sheets a predetermined profile.

Moreover, the devices for the carrying into effect of this invention are of simpler design, being also more economically operated than the already known types, and adapted to produce roughened, striped or longitudinally ribbed sheets, which are therefore particularly suitable for linings, coatings or the like.

It has been ascertained that short fibres may be advantageously employed for obtaining a product with high waterproof properties and strength, by reason of the peculiar distribution of the fibers caused by the action of the vibrating feeding hopper and of the vibro-compacting devices.

In the accompanying drawings, illustrative embodiments of the invention are shown, by way of example, but it is to be understood that it is possible to carry into effect the invention through other types of apparatus without departing from the scope of the invention. In the drawings:

Fig. 1 shows a diagrammatic cross-section of a machine for the continuous production of sheets.

Fig. 2 shows an endless travelling band, fitted on a machine of the kind shown in Fig. 1, for the continuous production of successive sheets of predetermined length.

Fig. 3 shows another machine for the continuous production of sheets having a predetermined length.

Fig. 4 shows a detail of the vibrating hopper of the device in Fig. 3.

Fig. 5 shows a detail of the vibrating compacting or compressing unit associated with the device of Fig. 3.

Fig. 6 shows a vacuum slide-valve, to be employed with the apparatus of Figs. 3 to 5, inclusive.

Referring first to Fig. 1, wherein an apparatus embodying the present invention is illustrated, reference numeral 1 indicates a rotatable hollow drum or cylinder having a porous or permeable peripheral wall and mounted for rotation about a horizontal axis. The opposite ends of the cylinder 1 are preferably sealed by end walls, and a unit is provided in the interior of the drum for exerting an inwardly directed suction effect on successive portions of the porous periphery of the cylinder, as the latter is rotated. This suction exerting unit includes angularly related 50 radial walls 2 and 4 held in fixed position with-

55 radial walls 2 and 4 held in fixed position with-

in the cylinder and extending from the axis of rotation of the latter substantially to the inside surface of the cylinder's porous periphery. Sealing elements 3 and 5 are carried by the outer edges of the walls 2 and 4, respectively, and engage slidably against the inner surface of the cylinder's periphery. A conduit connects to the space defined between walls 2 and 4, adjacent the junction of the latter, and leads to an evacuating device (not shown) of conventional construction for exerting a suction or vacuum against the inside of the portion of the cylinder's periphery located between the sealing elements 3 and 5. As the cylinder 1 rotates and the walls 2 and 4 are stationary, it is apparent that progressive sections of the cylinder's periphery are successively subjected to the suction or vacuum in the space between walls 2 and 4. As seen in Fig. 1, the walls 2 and 4 are angularly related by approximately 60°, with the wall 2 extending substantially vertically upward from the axis of rotation and with the wall 4 being inclined in the direction of rotation of the cylinder as indicated by the arrow. Thus, as the cylinder 1 is rotated, the periphery thereof is exposed to vacuum as it passes the uppermost position and continues to be so exposed for approximately the following 60° of rotation. The interior of cylinder 1, not included in the space between walls 2 and 4, is communicated with the atmosphere, so that, as the periphery of the cylinder moves past sealing element 5, the pressures inside and outside of the porous periphery are equalized and continue thus until the sealing element 3 is again reached.

A fabric or porous felt band 12 extends over at least that portion of the periphery of cylinder 1 which is defined between the sealing elements 3 and 5 and moves with the cylinder's periphery as the latter is rotated. Upon leaving the periphery at a point after sealing element 5, the band or web 12 is supported by a suitable conveyor 17, for example, a roller conveyor of conventional construction. The band or web 12 has a width slightly in excess of the width of the sheets to be formed thereon.

The mixture of fiber and cement, or other similar materials, from which the sheets are to be formed, is preferably in a pasty or damp condition, as distinguished from the wet mix or slurry employed in other processes for producing similar sheets, and is fed to the described machine through a suitable conduit 6. The conduit 6 discharges into a vibrated feeding hopper 7 which is located above cylinder 1 to distribute the mixture over band or web 12 as the latter contacts the periphery of cylinder 1 between sealing elements 5 and 3 and adjacent the latter. As seen in Fig. 1, hopper 7 includes a front wall 10, which, at its lower portion, extends parallel to the periphery of cylinder 1, and a rear wall formed by an upper section 8 and a lower section 9. The lower section 9 may be stationary, so that the section 8 moves relative thereto as the hopper is vibrated, or for the sake of simplicity may be secured to section 8 for movement with the latter. Side walls complete the hopper and may move with the front and back walls or be stationary. At least the front wall 10 and the rear wall section 8 are secured together and are mounted for vibrating motion in the direction of the two-headed arrow of Fig. 1 and about an axis 11 displaced forwardly of the front wall 10. Thus, as the hopper is vibrated, the lower portion of the front wall 10 acts to compress or compact the pasty or damp mix-

ture distributed on the surface of web or band 12. Since the underlying portion of the cylinder's periphery and hence the porous web 12 are subjected to a vacuum during the distribution and initial compacting of the mixture, water and air are withdrawn from the mixture into the space between walls 2 and 4 and then evacuated from that interior space by the vacuum producing device associated therewith. Further, the vacuum or suction acting on the under surface of band 12 during distribution of the mixture on the latter serves to ensure the even distribution of the mixture over the entire surface of the band subjected to the vacuum.

Arranged in front of the hopper 7, that is, spaced from the hopper in the direction of the rotation of cylinder 1, is a compacting or compressing device which includes a hammer or compacting member 13 mounted on an arm 14 pivotally mounted at 15 for vibratory movement in the direction of the two-headed arrow so that the member 13 subjects the sheet 16 being produced to repeated and rapid compacting blows during the terminal portion of the travel of the band 12 over the space defined between the seals 3 and 5. Thus, the remainder of the moisture and air occluded within the mixture is driven out of the sheet 16 and evacuated while the sheet is simultaneously compacted to increase the density and strength thereof.

When the band 12 has moved past the sealing element 5, and is no longer subjected to the vacuum effect, it is free to be removed from the peripheral surface of cylinder 1 and to be guided by the roller conveyors 17 with the plastic continuous sheet 16 thereon. In the device of Fig. 1, the band or web 12 is of substantially great length and is intended to be wound on and off two drums (not shown) located at opposite sides of the illustrated device as motion is imparted to the web or band by the rotated cylinder 1.

In the embodiment of the invention illustrated in Fig. 2, parts corresponding to those described in connection with the device of Fig. 1 are indicated by the same reference numerals. The embodiment of Fig. 2 is intended to continuously produce successive sheets of predetermined length rather than the one continuous sheet of indeterminate length produced with the previously described device. In order to continuously produce such successive sheets, the web of band 12 of the device in Fig. 2 is provided with solid or impervious ribs 18 rigidly fixed on the band and extending transversely on the latter. The ribs are slightly shorter than the width of the band, and slightly thinner than the sheet to be produced. The band 12 is a continuous element and passes over a loose or idler roller 19. 20 is a revolving brush with water sprayer, and diagrammatically represents a band washing device in place of which one of the already known beater types, having a beating action integrated with the water sprayer, might be employed. The walls 8 and 10 of the hopper 7, together with the vibrated compacting member 13, behave precisely as shaking tables, as in the embodiment of Fig. 1, and are suitably located and operated adjacent the cylinder surface. In the apparatus of Fig. 1 or 2 the mixture, which is continuously poured into the hopper 7 by the pipe 6, is uniformly and regularly fed on the band owing to the combined effect of the gravity, of vibrations, of the suction and of the forward motion of the band which is driven by the revolving porous or permeable cylinder.

A portion of the excess water, and the most of the air contained in the mixture, after filtering through the fabric band 12, flow through the porous peripheral wall of the cylinder, then are sucked into the space defined by the walls 2, 4 and sealing elements 3, 5 and exhausted by the associated vacuum pump. The wall 10 of the vibrating hopper acts, as already said, as a shaking table, by feeding the mixture and causing a first settling and compaction of the same. The mixture comes out of the hopper outlet in the form of a continuous sheet, with a sharply defined width determined by the side walls of the hopper.

Should a further compaction of the mixture appear necessary, it is performed by the shaking table or compacting device, acting on the sheet as a vibratory compressor or compactor simultaneously with the relative motion of the sheet carried by the band, and with the suction effect exerted inside of the length of cylinder defined between the seals 3 and 5.

In each of Figs. 1 and 2, only a single hopper is shown by way of example. In the practice, however, it may be necessary to employ several hoppers, acting successively, in order to produce a sheet composed by a number of superposed layers, of the same or different fibrous or non-fibrous material. The same can be said for the vibratory compacting device, of which more than one may be employed, with the purpose of repeating the compacting of the sheet, as well as smoothing and finishing the latter.

After the continuous sheet has been produced on the device of Fig. 1, the sheet is cut transversely as desired by means of one of the already known devices, such as automatic shears, a thin Carborundum wheel, or a suitably arranged bandsaw. The sheets so obtained can be submitted to further processing. Another band can be secured to the trailing end of band 12 so as to obtain a continuous production. The band 12, conveniently wound-up on a drum, can be employed again after having been washed.

The variation shown in Fig. 2, permits the elimination of all hand washing and manipulations of the band, since the band in this embodiment is of the endless type. Moreover, this arrangement is adapted for the continuous production of sheets already cut to the desired length. The ribs 18 fixed on the band and made of metal, rubber or leather, are slightly shorter than the width of the band, and slightly thinner than the sheet, and being impermeable eliminate the suction effect in the areas of the band covered by the ribs so that the mixture discharged onto the ribs is drawn off the latter onto the adjacent exposed areas of the band, no mixture remaining on the ribs, and consequently sheets can be obtained which are already cut and finished on all four sides. The numeral 17 in Fig. 2 is one of these finished sheets, and to take off the same, it is sufficient to lay on it a plate; with a curvature equal to that which shall be taken by the plastic sheet when, being no longer retained by the suction effect, it will only be subjected to the gravity action and will fall clear of the band 12.

The variation of Fig. 3, together with the corresponding details (Figs. 4, 5 and 6), shows apparatus for carrying the invention into effect, by which the practical requirements can be better fulfilled when cylinders of large diameter are employed.

The numeral 21 is the frame, on which the cyl-

inder 40, the axles 26 and 34, and the shafts 30 and 38 are fitted. The cylinder 40 is supported by the spokes 41 and by the hub 53.

In the embodiment of Fig. 3, the suction or vacuum is selectively applied to the periphery of cylinder 40 through a valve arrangement which includes a central valve member 52 fixed on the cylinder hub 53 and rotating with the latter on a cylinder supporting shaft 44. The valve member 52 is formed with a plurality of valve ports or passages a', b', c' . . . n' each of which opens radially at one end and axially at the other end thereof into an annular groove formed in a face of the member 52. The periphery of cylinder 40 is in the form of a hollow annular channel of substantially rectangular cross-section (Fig. 4) and having spaced radial partitions therein (Fig. 3) to divide the interior of that channel into a plurality of relatively sealed chambers a, b, c, . . . n, each having a porous or foraminous outer wall. Each of the cylinder chambers is connected to a radial pipe communicating the respective chamber with the radially opening end of the related port or passage of valve member 52.

An annular distributor member 45, fixedly mounted in relation to the frame 21, engages slidably in the groove formed in the face of valve member 52 (Fig. 6) and is formed with a hollowed out section 46 extending circumferentially for approximately 90° and opening axially at the side of the distributor engaging in the valve member groove for communication with the axially opening ends of the successive valve ports as the latter come into registry with the hollowed out section 46. A conduit 47 connects to the hollowed out section 46 and communicates the latter with a vacuum pump (not shown) or other similar device for establishing a vacuum or relatively low pressure in the hollowed-out section of distributor 45, and hence in those chambers of the cylinder periphery corresponding to the valve ports registering with the section 46. As shown by the dotted lines in Fig. 3, the hollowed-out section 46 is disposed to occupy the upper left quadrant of the circular path of the valve member 52, so that, with the cylinder in the position of Fig. 3, chambers l, m, n and a are subjected to the vacuum effect. As the cylinder 40 is rotated, in the direction of the arrow of Fig. 3, the chambers successively occupying the positions of the chambers l, m, n and a in that view are subjected to the vacuum effect. Seals 49 and 50 are carried by the distributor 45 and engage against valve member 52 to prevent leakage at the sliding surfaces of these elements.

As seen in Fig. 6, the distributor 45 is also formed with an annular slot 48 extending therethrough and reaching angularly from one end of the hollowed-out section 46 to the other end of the latter. The slot 48 serves to communicate the ports and the related chambers, not registering with the section 46, with the atmosphere so that, as a chamber moves past the position of chamber l in Fig. 3, such chamber is vented to the atmosphere to equalize the pressures at the opposite sides of the porous outer wall thereof.

A web or band of porous material may run over the cylinder 40, as in the previously described embodiments, or the sheets may be formed directly on the surface of the cylinder which is provided with circumferentially spaced transverse ribs 39 of impervious material, so that, as in the apparatus of Fig. 2, successive sheets of predetermined length are produced by reason of

75

the fact that the vacuum is only effective at opposite sides of the ribs to remove any mixture discharged onto the ribs for distribution over the intermediate areas between successive ribs.

The pasty or damp mixture is conveyed to the location of the machine by a duct 6 which discharges into a hopper 22 similar to the previously described hopper 1. Hopper 22 includes a front wall 25 having a lower portion formed to compact the mixture against the cylinder surface as the hopper is vibrated, a rear wall including an upper section 23 vibrating with the front wall and a lower section 24 which may be formed of resilient material, such as rubber, to permit the ribs 39 to pass under the hopper to finish the side edges of the sheets during the final compacting of the latter.

In operation, the apparatus of Fig. 3 performs substantially in the same manner as the devices described in connection with Figs. 1 and 2. When a section of the cylinder arrives under the hopper 22 and is subjected to the vacuum effect, the pasty mixture is discharged onto the cylinder in the form of a sheet and is initially compacted by the vibrated front wall 25 of the hopper so that the removed water and air are drawn inwardly through the porous cylinder periphery into the underlying cylinder chamber for evacuation by the vacuum pump.

When, owing to the revolving motion of the cylinder, a sheet is brought out from under the compacting element 32 and the pressures at opposite sides of the cylinder wall are equalized, the sheet is removed in the manner previously described, while on the opposite side of the cylinder the latter is cleaned or fresh washed bands are applied thereto. The band might, at will, be fixed to the cylinder or replaced by another equivalent means, or wholly eliminated.

In Fig. 3 there are shown, by way of example, 12 chambers and 6 ribs 39, so as to produce 6 sheets for each revolution of the cylinder.

However, in the practice it is possible to subdivide the cylinder in whatever number of chambers may be desired for producing any desired number of sheets at each revolution of the cylinder.

Moreover, the apparatus shown in Fig. 3 can be provided with the endless band or web of Fig. 2, with or without the ribs 18, or with an elongated web combined with or without the roller table 17 of Fig. 1.

It should be noted that with the apparatus and process heretofore described, the thickness of the sheet can be varied from point to point of its cross-section by suitable shaping of the hoppers, cylinder surfaces and compacting elements. Therefore, it is possible to produce longitudinally striped or ribbed sheets, since this exclusively depends from the profile of the hopper-wall 25, and of the vibratory counter-mold or compacting elements 31 and 32.

As in the embodiments of Figs. 1 and 2, the apparatus of Fig. 3 may include more than one hopper so that sheets may be produced which are composed of successive layers of the same or different mixtures.

Having now particularly described and ascertained the nature of my said invention and in what manner the same is to be performed, I declare that what I claim is:

1. A device for making cement-asbestos sheet material comprising a revolving drum rotating about a horizontal axis and having a permeable cylindrical wall, a permeable belt travelling

around said drum for an angle of less than 360°, means for creating a vacuum at the inside of part of the portion of said cylindrical wall covered by said belt, a hopper for discharging a pasty cement-asbestos mixture downwardly onto the initial portion of said part of the belt and including a surface lying against said initial portion of said part of the belt on said drum, a second surface lying on said belt in succession after said first mentioned surface, means for oscillating said first mentioned and said second mentioned surfaces in directions angularly disposed to said respective surfaces, and means for removing the material formed on said belt after the belt has left the drum.

2. Apparatus for the continuous production of cement-fiber sheets comprising a rotatable cylinder mounted for rotation about a horizontal axis and having a porous peripheral wall, a hopper disposed for discharging a pasty cement-fiber mixture downwardly onto said wall of the cylinder and including a hopper wall section extending along and adjacent to a portion of said peripheral wall of the cylinder, means for vibrating said hopper wall section in the direction radially of said cylinder, means for creating a vacuum at the inside of said peripheral wall and over a zone extending from the location of said hopper in the direction of rotation for less than 360°, compacting means disposed adjacent said peripheral wall at the terminal portion of said vacuum zone and including a rockable member mounted at its center for swinging about an axis parallel to said axis of the cylinder, compacting elements at the opposite ends of said rockable member to engage the mixture on said peripheral wall, and means for oscillating said rockable member so that said compacting elements serve to compact the mixture, and means for removing the mixture from the peripheral wall after the latter has moved beyond the terminal end of said vacuum zone.

3. Apparatus according to claim 2; wherein said compacting elements are adjustable relative to said rockable member in the direction radially of said cylinder to control the engagement thereof with the mixture on the peripheral wall so that the compacting action of said elements may be equalized.

4. Apparatus according to claim 2; wherein said compacting elements are formed with projections at the opposite ends thereof for finishing the side edges of the mixture on said peripheral wall.

5. Apparatus according to claim 2; including a filtering web running over said peripheral wall and in contact with the latter at least throughout said vacuum zone.

6. Apparatus for the continuous production of cement-fiber sheets comprising a cylinder rotatable about a horizontal axis and having a porous peripheral wall, a hopper disposed for discharging a pasty cement-fiber mixture downwardly onto said peripheral wall, means for creating a vacuum at the inside of said peripheral wall and over a zone extending from the location of said hopper in the direction of rotation of the cylinder for less than 360°, impervious ribs extending transversely of said peripheral wall and movable with the latter to render the vacuum ineffective at the underlying areas of said peripheral wall whereby the discharged mixture is collected by the vacuum at the areas of said peripheral wall disposed between successive impervious ribs, means for compacting the mixture on said pe-

9

peripheral wall during passage through said vacuum zone, and means for removing the compacted mixture from said peripheral wall after passage out of said zone.

7. Apparatus according to claim 6; including an elongated filtering web carrying said ribs and contacting said peripheral wall at least throughout said zone for receiving the discharged mixture.
